US00D841652S

(12) **United States Design Patent** (10) **Patent No.:** **US D841,652 S**
(45) **Date of Patent:** **** Feb. 26, 2019**

(54) **ADAPTER**

- (71) Applicant: **Apple Inc.**, Cupertino, CA (US)
- (72) Inventors: **Jody Akana**, San Francisco, CA (US); **Bartley K. Andre**, Palo Alto, CA (US); **Jeremy Bataillou**, San Francisco, CA (US); **Daniel J. Coster**, San Francisco, CA (US); **Daniele De Iuliis**, San Francisco, CA (US); **M. Evans Hankey**, San Francisco, CA (US); **Julian Hoenig**, San Francisco, CA (US); **Richard P. Howarth**, San Francisco, CA (US); **Jonathan P. Ive**, San Francisco, CA (US); **Duncan Robert Kerr**, San Francisco, CA (US); **Shin Nishibori**, Kailua, HI (US); **Matthew Dean Rohrbach**, San Francisco, CA (US); **Peter Russell-Clarke**, San Francisco, CA (US); **Christopher J. Stringer**, Woodside, CA (US); **Eugene Antony Whang**, San Francisco, CA (US); **Rico Zörkendorfer**, San Francisco, CA (US)
- (73) Assignee: **Apple Inc.**, Cupertino, CA (US)
- (**) Term: **15 Years**
- (21) Appl. No.: **29/581,997**
- (22) Filed: **Oct. 24, 2016**

Related U.S. Application Data

- (63) Continuation of application No. 29/557,994, filed on Mar. 14, 2016, now Pat. No. Des. 769,877, and a continuation of application No. 29/557,995, filed on Mar. 14, 2016, now Pat. No. Des. 770,456, which is a continuation of application No. 29/530,282, filed on Jun. 15, 2015, now Pat. No. Des. 751,560, which is a continuation of application No. 29/477,506, filed on Dec. 23, 2013, now Pat. No. Des. 732,035, said application No. 29/557,994 is a continuation of application No. 29/530,282, filed on Jun. 15, 2015,

now Pat. No. Des. 751,560, said application No. 29/477,506 is a continuation of application No. 29/456,487, filed on May 31, 2013, now Pat. No. Des. 707,681, which is a continuation of application No. 29/431,556, filed on Sep. 7, 2012, now Pat. No. Des. 684,976.

CLAIM

The ornamental design for an adapter, as shown and described.

DESCRIPTION

FIG. 1 is a top front perspective view of an adapter showing the claimed design;

FIG. 2 is a bottom rear perspective view thereof;

FIG. 3 is a front view thereof, the rear view being a mirror image thereof;

FIG. 4 is a side view thereof, the other side view being a mirror image thereof;

FIG. 5 is a bottom view thereof; and,

FIG. 6 is a top view thereof.

The dashed broken lines in the figures show portions of the adapter that form no part of the claimed design.

The dot-dash broken lines in the figures show boundaries that form no part of the claimed design.
